(57) CLAIM

The ornamental design for a shoe, as shown and described.

DESCRIPTION

FIG. 1 is a bottom view of a shoe showing my new design; FIG. 2 is a side view thereof; and, FIG. 3 is an opposite side view thereof.

The broken lines immediately adjacent to ends of the shaded area define the bounds of the claimed design and form no part thereof. The broken lines inside the five linear elements on the central bottom of the shoe and the unshaded regions therein form no part of the claimed design. The remainder of the shoe shown in a lighter grey photographic depiction forms no part of the claimed design.
